UNIVERSAL SHELF DIVIDER LOCKING DEVICE

Clarence F. Block, Barrington, Ill., assignor to Production Metal Products Co., Inc., Chicago, Ill.

Filed Oct. 16, 1973, Ser. No. 406,943

Term of patent 14 years

Int. Cl. D8—08

U.S. Cl. D8—109

FIG. 1

FIG. 2

FIG. 3

FIG. 4

FIG. 5

FIG. 1 is a perspective view of a universal shelf divider locking device embodying my new design.

FIG. 2 is a top plan view of the universal shelf divider locking device shown in FIG. 1.

FIG. 3 is a bottom view of the universal shelf divider locking device shown in FIG. 1.

FIG. 4 is a front view of the universal shelf divider locking device shown in FIG. 1.

FIG. 5 is a side view of the universal shelf divider locking device shown in FIG. 1.

I claim:

The ornamental design for a universal shelf divider locking device, substantially as shown and described.
